UNITED STATES PATENT OFFICE.

OSCAR M. SHECK, OF CLEVELAND, OHIO, ASSIGNOR TO THE ARGUS LAMP AND APPLIANCE COMPANY, OF CLEVELAND, OHIO.

ADJUSTABLE LAMP BRACKET.

1,257,130.

Specification of Letters Patent. Patented Feb. 19, 1918.

Application filed July 7, 1917. Serial No. 179,275.

To all whom it may concern:

Be it known that I, OSCAR M. SHECK, a citizen of the United States, residing at Cleveland, in the county of Cuyahoga and State of Ohio, have invented certain new and useful Improvements in Adjustable Lamp-Brackets, of which the following is a specification.

This invention relates to lamp brackets, 10 and more particularly to the supporting means or brackets for what are commonly known as spot-lights employed for stage lighting. In practice the spot-light apparatus is generally located in a desirable position off the stage, usually in the front of the balcony of the auditorium, the purpose being to project light rays in a field confined to a spot the area and location of which, relative to the otherwise darkened stage is 15 governed by the adjustments of the apparatus and the lamp which is a part thereof.

The lamp houses in general use for spot lighting have an oscillating and a tilting movement already provided for, and the 20 present invention relates to a lamp bracket having certain adjustments relative to the lamp, use and lens.

The object of the invention is to provide simple and economical means for easily and 25 quickly focusing and otherwise adjusting the lamp to meet requirements not provided for by the tilting or other movements of the lamp house, and to provide a construction of bracket that can be readily applied to 30 lamp houses already installed, with but slight alteration to said houses. With these 35 objects in view the invention consists in the construction, arrangement and combination of the parts as hereinafter described and 40 pointed out definitely in the claims, reference being had to the accompanying drawing forming a part of the specification, and in which similar characters of reference are employed to designate similar parts.

45 In the said drawing Figure 1 is an elevation of an embodiment of the improved bracket showing a portion broken away.

Fig. 2 is a central vertical section on line 2—2 Fig. 3, and Fig. 3 is a transverse section on line 3—3 Fig. 2.

In a former application filed by me April 24th, 1917, Serial No. 164,313, I have described and claimed a lamp carriage with the same objects in view as set forth above, 55 my present invention however provides a

simpler and more economical and convenient construction, as will readily be seen.

Referring now to the several figures of the drawing, 1 represents a socket supporting member or head, to which the ordinary lamp socket 2 is attached. The supporting head 1 is made of suitable insulating material and is provided with a tubular stem 3. A bifurcated base plate, or track 4 is adapted to be secured to the floor of the lamp house, and a block 5 provided with parallel longitudinal channels 5^a is slidably connected with said track, the channels 5^a accommodating the branches 4^a, said branches forming ways on which the block 5 slides. A set screw 6 provides means for locking the block 5 to the track 4 at any desired longitudinal location.

A tubular member or sleeve 7 is firmly attached to the block 5 and depends therefrom between the members 4^a. The bore of the sleeve 7 accommodates the stem 3, the said stem extending entirely through said bore and having a sliding fit therein. The lower terminal of the member 7 is split as shown at 7^a, and is provided with a tapered thread 7^b on which is threaded a knurled nut 8, said nut of course having a tapered thread to fit the thread on member 7.

It will readily be seen that with the nut 8 threaded downward on the taper 7^b the stem can be raised or lowered in the bore of the sleeve 7, and when the said stem is at the desired elevation the nut 8 being tightened on the thread 7^b will cause the split portion 9^a of the member 7 to contract and clamp the stem 3, thereby retaining the stem as adjusted and thus provide vertical adjustment to the lamp 9.

The electric conductors *a* and *b* which are 95 operatively connected with the lamp socket extend through suitable apertures in the insulated head 1 and pass through the bore 3^a of the stem 3.

The device provides simple, universal adjustment and the sleeve member 7 provides a convenient means for manually operating the block in its sliding adjustment on the track member 4 when the set screw 6 is not binding on said plate.

105 What I claim and desire to secure by Letters Patent is,

1. In an adjustable lamp bracket the combination of a supporting block provided with channels; permanent track members 110

extending through said channels and on which said block is slidable; a sleeve attached to said block between the track members; a lamp socket base provided with a tubular stem which passes through said sleeve, the free end of said sleeve being split and provided with a tapered thread; and a nut operative on said tapered thread.

2. In an adjustable lamp bracket the combination of a supporting block provided with channels; permanent track members extending through said channels and on

which said block is slidable; means for clamping said block to the track; a sleeve attached to said block between the track members; a lamp socket base provided with a tubular stem which passes through said sleeve the free end of said sleeve being split and provided with a tapered thread; and a nut operative on the tapered thread. 15

In testimony whereof I affix my signature. 20
OSCAR M. SHECK.

Witness:

FRANK R. BLAKESLEE.
